Inventor:

William Parkin

United States Patent Office.

WILLIAM PARKIN, OF TAUNTON, MASSACHUSETTS, ASSIGNOR TO REED & BARTON, OF SAME PLACE.

Design No. 4,437, dated October 25, 1870.

DESIGN FOR TABLE-CASTERS.

The Schedule referred to in these Letters Patent and making part of the same.

To all whom it may concern:

Be it known that I, WILLIAM PARKIN, of Taunton, in the county of Bristol and State of Massachusetts, have invented and produced a new and original Design for Caster and Bottle; and I do hereby declare the following to be a full, clear, and exact description of the same, reference being had to the accompanying drawings making a part of this specification, in which—

Figure 1 is a side elevation of the caster, with the bottles in place.

Figure 2, a top view of the caster without the bottles.

Figure 3, a perspective view of one of the bottles.

This invention relates to the form and ornamentation of casters for table use, and consists in the peculiar design hereinafter described.

In the drawings—

A represents the square bottom plate of the caster, supported on four curved legs, α α , representing, at α , an animal's claw.

The legs extend above the corners of the plate, curving outward, and terminating, at their upper extremities, in the figure of a swan, with head resting on its breast, and expanded wings, resting against and supporting the outer corners of the bottle-racks r r .

These racks are square, and are supported at the outer corner as above described, and at the inner corner, diagonally opposite, by a flat horizontal plate, P, which is in its turn upheld by means of the handle or central stem S.

The latter is bifurcated at s, and the upper ends of the forks are surmounted by circular knobs, s' s', and connected together by a curved rod, t, having an ornamented shield, e, at its center.

The bottles are of an oriental pattern, any horizontal section of them, except at the lip-flange, being a square, and through that flange circular. Their shoulders swell out with an even, graceful curve from the neck, and below the shoulders they diminish slightly in diameter to their lower end. Their flat sides are ornamented with flowers, leaves, or other design, and their corners are notched or serrated.

The cruets have glass stopples, with nearly square heads, terminating at their upper end in a flat pyramid, with smooth beveled corners, their vertical corners being beveled and notched in the same manner as the bottles.

The pepper-box, mustard-box, &c., have silver caps, with smooth, conical crown, terminating in a little spire. In other respects they are similar to the cruets, differing only so far as is rendered necessary by the different use to which they are to be put.

Having thus described my invention,

What I claim as new, and desire to secure by Letters Patent, is—

The design for a table-caster, as herein described and shown.

WILLIAM PARKIN.
